ELASTIC FLUID DUST SEPARATING AND COLLECTING SYSTEM

Filed Aug. 14, 1928

FIG. 2

FIG. 1

George M. Spencer INVENTOR

BY

ATTORNEY

UNITED STATES PATENT OFFICE

GEORGE M. SPENCER, OF ST. LOUIS, MISSOURI

ELASTIC-FLUID DUST SEPARATING AND COLLECTING SYSTEM

Application filed August 14, 1928. Serial No. 299,471.

My invention is shown herein as embodied in a novel construction comprising a centrifugal chamber to mass and separate the material at the outer edge of the air stream, an exhaust and dust exit at the outer edge of the chamber, and a dust trapping member at the outer edge of the air stream to brush the massed particles free of the air stream and into the mouth of a dust hopper. The separation of dust particles is aided by a non-chokable filtering mass within an interior chamber to collect any extremely small particles which may reach such chamber. The friction between the stream of air and the walls of the device is reduced to a minimum, and all parts are arranged in a compact operating unit, instantly accessible without the use of tools or skill. The device is provided with an automatic clean-out means, and operates efficiently throughout wide variations of rate of flow.

I prefer to make the device from sheet metal with standard lap, riveted, or brazed means although some of the small sized structures may be made from cored castings.

Referring to the accompanying drawing, in which an embodiment of the invention is shown,

Fig. 1 is a view in vertical section, showing the parts as assembled; and

Fig. 2 is a top plan view, the structure of certain of the parts being shown in dotted line.

As shown in Fig. 1 a walled circular top section 5, and a lower hopper section 6, with a dust exit at the lower end thereof, are connected at a separable sleeve joint 7. An inlet connection 8 is provided, extending through the side wall of the top casing 5. An outlet tube 9 having a flanged collar 10 between its ends, extends through the central portion of the top casing 5 and is brazed thereto, one end 12 forming an outlet lead to atmosphere, or for return to a supply source, when the operation is made through a closed system.

The top section 5 has a circular floor plate 13, the central portion of which is perforated to fit the outer wall of tube 9 and is brazed thereto, the plate being spaced from

the top and side walls of the top section 5 to form an annular chamber 14. One wall 11 of the inlet connection 8 extends tangentially to the outer wall of the tube 9, to direct the air tangentially into the chamber 14. The space between the outer rim of the plate 13 and the side wall of the top section 5 provides a narrow, elongated exhaust and dust exit 15 at the outer edge of the chamber 14. A dust trapping and deflecting brush 16, formed of hair or slender wire strands, is secured to the wall of chamber 14, such member preferably taking the form of an annular brush attached at its upper edge to the wall of the top section 5 and composed of filaments, the lower ends of which are free and extend downwardly and inwardly into the inlet 15, so that the air current causes them to vibrate and any dust particle not deflected through the strands will gravitate downward. Due to the flexibility and positioning of the filaments of the deflecting means 16, the rebounding of particles is prevented and the dust collecting efficiency increased, since any particle which engages the deflecting means can never be returned into the air stream.

Within the lower hopper section 6 an inner hopper section 20 is positioned in coaxial relation and preferably held in place, with its sloping walls uniformly spaced from the hopper section 6, by a plurality of narrow bars 21. At its top the inner hopper section 20 has a cylindrical wall 18, the upper edge of which terminates somewhat below the corresponding upper edge of the hopper section 6, so that it is slightly spaced from the plate 13 to form a narrow circumferential passage 17.

A filtering mass 22 of loosely packed fibrous material such as curled hair, is loosely held in place within the top of the inner hopper section 20, being preferably supported on a wire screen disk 19 which fits in the hopper at the angle formed at the bottom of the cylindrical wall 18, and a second wire screen disk 28 is preferably provided at the top of the filtering mass to engage the lower open end of the outlet tube 9. It will be understood that the filtering mass may be

formed of materials other than hair, such as fibers, metallic filaments or a mixture of such filamentary materials. The structure of the filtering mass should be such that the air may easily pass through it yet sufficiently dense that the dust particles which may be still entrained in the air stream as it enters the narrow opening 17 will engage the strands and be deflected or stopped, and, as the filtering mass is vibrated, will settle by gravity through the filtering mass and wire screen 19 and fall into the lower portion of the hopper 20.

The lower end of the inner hopper 20 is provided with a tubular portion 23 which terminates within a mouth formed at the bottom of the outer hopper 6, an annular outlet for the hopper 6 being thus provided about the outlet of the inner hopper 20. A light disk valve member 24, for simultaneously closing both outlets, is slidably carried on a rod 25 which extends downwardly in the tubular portion 23, and is supported at its top from a cross bar 26 positioned in the inner hopper 20. It will be apparent that the valve 20 will open and close with pulsations of the air passing through the device to permit accumulated dust particles to fall out of the hoppers 6 and 20, and, if the device is used under conditions where there would be no pulsation of the air stream or where the pressure within the hoppers would be above atmospheric pressure, the valve 24 may be replaced by a suitable removable cap.

If the air carries a considerable quantity of comparatively large dust particles, or if it is desired to sort out the coarser dust particles, an auxiliary hopper 30 is used, through which the air is passed before entering the inlet 8. As shown, the auxiliary hopper 30 has a tubular inlet 29, which is expanded at 32, and a laterally extending tubular outlet 33, adapted to fit the inlet 8 of the top section 5. The auxiliary hopper 30 is preferably composed of a top portion, in which the inlet and outlet are formed, a body portion and a removable cap 31 for closing an opening at the bottom of the body portion to facilitate removal of the collected particles, and a deflecting member 34, which may take the form of a perforated plate or screen mesh, is secured to the top portion and curved across the entrance to the outlet 33 to prevent particles of any considerable size from entering such outlet.

The hopper 30 will act as a momentum separator to collect the larger dust particles, and as the air passes through outlet 33 and inlet 8 into chamber 14 the cyclonic action will centrifugally force any dust particles which may be still entrained in the air stream toward the outer cylindrical wall of the chamber 14 and, as the air passes downwardly through the peripheral opening 15,

will strike the filaments of the deflecting brush 16 and be deflected or fall into the bottom of the outer hopper 6 about the tubular portion 23. From the opening 15 the stream of air follows a laterally and upwardly curving path to enter laterally into the narrow elongated opening 17, being then again directed downwardly by the protruding end of the outlet tube 9 so that, to reach the outlet tube 9 it must follow a laterally and upwardly curving path through the fibrous filtering mass 22 which will de-train from the air stream any fine particles which may remain and permit them to settle by gravity into the bottom of the inner hopper 20 and the tubular portion 23.

While one embodiment of the invention has been shown and described, it will be understood that many changes may be made in the structural details within the scope of the following claims in which the invention is defined.

I claim:

1. An air cleaner comprising a casing having a body portion and a cover portion, said cover portion having an outlet therein, a diaphragm having a part of its edge spaced from the wall of said casing to define a narrow peripheral passageway, and an interior casing surrounding the lower end of said outlet and having its upper edge spaced from said diaphragm and inwardly from the periphery thereof.

2. An air cleaner comprising a casing having a body portion and a cover portion, a diaphragm having a part of its edge spaced from the wall of said casing to define a narrow peripheral passageway, an outlet tube extending downwardly through said diaphragm, and an interior casing surrounding the lower portion of said outlet tube with its upper edge above the lower edge of said outlet tube and spaced from said diaphragm inwardly from the periphery thereof.

3. An air cleaner comprising a casing having a body portion and a cover portion, a diaphragm having a part of its edge spaced from the wall of said casing to define a narrow peripheral passageway, an outlet tube extending downwardly through said diaphragm, said casing having a tangentially directed inlet above said diaphragm, an interior casing having its upper edge spaced from said diaphragm between said outlet tube and the periphery of said diaphragm, and a filtering medium supported in the upper portion of said inner casing.

4. An air cleaner comprising an outer casing, an inner casing having its walls spaced from those of said outer casing, and a diaphragm substantially closing the tops of said casings, having at least part of its edge spaced inwardly from the wall of said outer casing to form a narrow peripheral inlet to direct the air downwardly between said cas-

ings and spaced from the top edge of said inner casing to define a narrow inlet to direct the air laterally to the top of said inner casing.

5. An air cleaner comprising a casing, a diaphragm having a part of its edge spaced from the wall of said casing to define a narrow peripheral passageway, and a filter member arranged in said passageway and comprising a plurality of perpendicularly disposed filaments.

6. An air cleaner comprising a casing, a diaphragm within said casing and peripherally spaced from the wall of said casing 15 to define a narrow peripheral passageway, a cover closing the top of said casing and having a tangentially directed inlet, and a curved brush arranged in the peripheral passageway and comprising a plurality of downwardly 20 directed filaments.

7. An air cleaner comprising a casing, a diaphragm substantially closing said casing having a part of its edge spaced from the wall of said casing to define a narrow peripheral passageway, and a filter member arranged adjacent to and extending downwardly and inwardly from said passageway.

8. An air cleaner comprising a casing, a diaphragm substantially closing the top of 30 said casing and having a portion thereof peripherally spaced from the wall of said casing to define a narrow passageway, a cover closing the top of said casing and having a tangentially directed inlet above said diaphragm, and filtering means supported adjacent said passageway and extending downwardly therefrom.

9. An air cleaner comprising a casing, a diaphragm substantially closing the top of 40 said casing and having a portion thereof peripherally spaced from the wall of said casing to define a narrow passageway, a cover closing the top of said casing and having a tangentially directed inlet, and a brush 45 supported adjacent the narrow inlet into said casing and comprising a plurality of filaments extending downwardly from said passageway.

GEORGE M. SPENCER.
